CHARLES A. OLcott, OF NEW YORK, N. Y., ASSIGNOR TO S. S. HEPWORTH COMPANY, OF NEW YORK, N. Y., A CORPORATION OF NEW YORK.

CENTRIFUGAL MACHINE.

Application filed June 3, 1925. Serial No. 34,642.

My invention relates to centrifugal machines, and particularly to centrifugal driers. The object of my invention is to prevent discharged fluid from being carried up and out of the centrifugal casing by the air current which escapes from the area between the basket and casing during the operation of the machine.

In the accompanying drawings—
10 Fig. 1 is a broken side elevation of the basket and casing of a centrifugal to which my invention is applied in one form; and

Fig. 2 is an inverted plan of the casing cover.
15 When operating a centrifugal for drying sugar, the sugar-carrying molasses which is fed into the centrifugal basket 3 on driving shaft 4, discharges through the perforations 5 in the wall 6 of the basket. Surrounding the basket is the usual stationary casing 7, against which the molasses impinges, and down the walls of which it tends to flow. An annular cover 8 is commonly provided at the top of the casing to prevent 20 spatter, as well as to guard the attendant.

When the basket is in operation, an air current is established which flows from the space 9 between the basket and the casing 7, both upward and downward, escaping below through the open lower end of the casing, and upward through the central opening in the cover 8. A certain whirling motion is imparted to the air current by the rotation of the basket. This upwardly flowing and whirling current of air, causes some 30 of the molasses to creep upward and along the under surface of the cover 8 until it reaches the lip 10, from which it is blown out upon the attendant.

40 I have found that this objectionable operation may be avoided by providing the inner surface of the cover with ribs 11 which not only baffle the whirling air current at this point, but also form guides along which 45 the liquid is caused to travel outward toward the casing 7 by the air current which, in the first instance, drags it upward and inward. Preferably the ribs 11 extend the entire width of the cover and are arranged 50 on a curve traversing the whirl of the air

current, but extending in the same general direction.

When the liquid dragged by the air to the cover and partially across the latter, reaches the ribs 11, it is caused by the wind pressure 55 to move outward along the latter to the outer periphery of the cover, and is thus kept away from the inner lip 10. If any particles of liquid are carried upward in suspension by the air current, they are deposited by the ribs, which act as baffles, and follow the latter outward to the periphery of the cover in a similar manner. Moreover, the ribs 11 tend to baffle the air current itself, and to deflect portion of it and to set up 60 eddies which arrest its upward flow and its whirling motion, thus reducing the celerity of the current as it passes the lip 10 of the cover.

Various modifications in the form of the 70 ribs 11 may be made. Straight ribs may be employed, or interrupted rather than continuous ribs, but I have found the curved uninterrupted ribs to give most satisfactory results.

I claim as my invention—

1. In a centrifugal machine, a stationary casing for the centrifugal basket, an inwardly extending annular cover for the casing, and means on the inner face of the 80 cover causing outward flow of liquid entrained by the current of air escaping at the inner margin of the cover during the operation of the machine.

2. In a centrifugal machine, a stationary casing for the centrifugal basket, an inwardly extending annular cover for the casing, rib means on the inner surface of the cover for directing outward liquid entrained by the air current which flows upward within 85 the casing and inward to the inner margin of the cover during the operation of the machine.

3. In a centrifugal machine, a stationary casing surrounding a centrifugal basket, an inwardly extending annular cover for the casing, and curved ribs on the inner surface of the cover for causing the outward flow of liquid entrained by the air current which flows upward within the casing and inward 95 100

to the inner margin of the cover during the operation of the machine.

4. In a centrifugal machine, a stationary casing for the centrifugal basket, an inwardly extending annular cover for the casing, and ribs on the inner face of the cover, said ribs extending from the inner toward

the outer portion of the cover in the general direction of, but traversing the course of, the air current set up by the operation of 10 the machine.

In testimony whereof I have signed my name to this specification.

CHARLES A. OLCOTT.
